UNITED STATES PATENT OFFICE.

AUGUST ROOS, OF NEW YORK, N. Y.

FILTER.

SPECIFICATION forming part of Letters Patent No. 278,186, dated May 22, 1883.

Application filed January 24, 1883. (No model.)

To all whom it may concern:

Be it known that I, AUGUST ROOS, a citizen of the United States, residing at New York, in the county and State of New York, have 55 invented new and useful Improvements in Filters, of which the following is a specification.

This invention relates to a filter the filtering-chamber of which can be revolved on a stationary hollow shaft, the liquid to be filtered 10 being introduced at one end of this shaft and discharged at its opposite end.

The peculiar construction of my filter is pointed out in the following specification and 15 illustrated in the accompanying drawings, in which—

Figure 1 represents a vertical section in the plane $x x$, Fig. 2. Fig. 2 is a similar section in the plane $y y$, Fig. 1.

Similar letters indicate corresponding parts.

20 In the drawings, the letter A designates a stationary shaft, which has its bearings in standards B B, rising from the bed-plate C, or which may be supported by any other suitable means. The central part of this shaft is solid; 25 but its ends are bored out to form channels b b' , the channel b being connected to the liquid-supply pipe P, and the channel b' to the liquid-discharge pipe P' .

On the solid portion of the shaft A is mounted 30 the filtering-vessel D, the filtering material being placed into the filtering-chamber d , which is partitioned off from the chambers d' d^2 by sieves d^3 .

The outer surfaces of the hollow portions of 35 the shaft A form plugs e e' , which fit, respectively, into tubular shells E E', projecting from heads F F', which are firmly secured to the heads of the filtering-vessel D by bolts f f' . From the shell E extend two pipes, G G*, in 40 opposite directions, and the outer end of the pipe G communicates with the chamber d' of the filtering-vessel, while the outer end of the pipe G* communicates with the chamber d^2 .

From the shell E' extend the two pipes G' 45 G**, which communicate with the chambers d' d^2 , respectively, in the same manner as the pipes G G*. In the plugs e e' are openings g g' , respectively, but on opposite sides of said plugs, the opening g in the plug e being on the upper side and the opening g' in the plug e' being on the under side, as shown in Fig. 1.

The chamber d' is provided with a cleaning-cock, H, and the chamber d^2 with a cleaning-cock, I. In the bed-plate C is secured a waste-pipe, J, with a funnel-shaped mouth-piece. The 55 filtering-chamber d is provided with hand-holes h h , Fig. 2, through which the filtering material can be introduced or removed.

K, Fig. 1, is a latch which engages with a cavity, k , in the shell E and retains the filtering-vessel in position. When this latch is raised the filtering-vessel can be turned round on the shaft A. In the example shown in the drawings the latch K is hinged to one of the standards B; but said latch may be made in 65 any form adapted to lock the filtering-vessel in the required position. In the outer ends of the shells E E' are formed stuffing-boxes l l' , respectively, so as to prevent leakage between the plugs e e' and the shells E E'.

In the position shown in Fig. 1 the water or other liquid to be filtered (the stop-cocks p p' being open) passes through the channel b and pipe G into the chamber d' , from this chamber through the filtering material in the chamber d into the chamber d^2 , thence through the pipe G** and channel b' to the discharge-pipe P' . After some time the filtering material becomes charged with impurities, and in order to wash out these impurities the latch K is 70 raised, the filtering-vessel D is turned round on the shaft A, the stop-cock p' is closed, and the cleaning-cock H is opened, and the water or other liquid admitted through the pipe P now passes through the pipe G* into the chamber d^2 , thence through the filtering material 75 into the chamber d' , and through the cleaning-cock H into the waste-pipe J, carrying with it the impurities which have accumulated in the filtering material. When the filtering material 80 has thus been cleared the cleaning-cock H is closed and the stop-cock p' is opened, when the filtering operation continues, as previously described.

In the example shown in the drawings the 95 pipes G G* G' G** pass into chambers d' d^2 , which are separated from the filtering material by sieves d^3 . If the openings of the pipes G G* G' G** and of the cocks H I are protected by sieves, the filtering-vessel may be filled clear 100 up with filtering material; but by forming the chambers d' d^2 in the filtering-vessel a more

uniform distribution of the liquid to be filtered through the filtering material is effected.

What I claim as new, and desire to secure by Letters Patent, is—

- 5 1. The combination of the bearings B, the shaft A, fixed in a stationary position in said bearings, and having channels b b' formed in its ends, liquid supply and discharge pipes provided with stop-cocks p p', the filtering-vessel D, capable of rotating on the shaft, and constructed with the opposite chambers, d' d², and the cleaning-cocks H and I, connecting, respectively, with said chambers, and channels G G* G' G'*, connected and rotating with the filter, substantially as described.
- 10 2. The combination of the stationary shaft

A, having the channels b b' in its ends, communicating with supply and discharge pipes, respectively, the filtering-vessel D, arranged to be rotated on the stationary shaft, and composed of the filtering-chamber d, the two chambers d' d², heads F F', and cleansing-cocks H I, and the shells E E', provided with the channels G G* G' G'*, substantially as described.

In testimony whereof I have hereunto set 25 my hand and seal in the presence of two subscribing witnesses.

AUGUST ROOS. [L. S.]
